(57) **CLAIM**

What is claimed is the measuring device, in particular for measuring the level of liquid gas within a container, as shown and described.

DESCRIPTION

FIG. 1 shows a perspective view of an embodiment of the measuring device, in particular for measuring the level of liquid gas within a container according to the disclosure.

FIG. 2 shows a top view of the embodiment of the measuring device, in particular for measuring the level of liquid gas within a container according to the disclosure.

FIG. 3 shows a bottom view of the embodiment of the measuring device, in particular for measuring the level of liquid gas within a container according to the disclosure.

FIG. 4 shows a first side view of the embodiment of the measuring device, in particular for measuring the level of liquid gas within a container according to the disclosure.

FIG. 5 shows a second side view of the embodiment of the measuring device, in particular for measuring the level of liquid gas within a container according to the disclosure.

FIG. 6 shows a front view of the embodiment of the measuring device, in particular for measuring the level of liquid gas within a container according to the disclosure; and,

FIG. 7 shows a rear view of the embodiment of the measuring device, in particular for measuring the level of liquid gas within a container according to the disclosure.

The dashed line portion forms no part of the claim.
